UNITED STATES PATENT OFFICE

163,472

COMBINED EGG SERVING CUP AND SAUCER

Thorwald R. Nelson, Hollywood, Calif.

Application January 23, 1951, Serial No. 13,916

Term of patent 3½ years

(Cl. D44—9)

To all whom it may concern:

Be it known that I, Thorwald R. Nelson, a citizen of the United States, residing at Hollywood, in the county of Los Angeles and State of California, have invented a new, original, and ornamental Design for a Combined Egg Serving Cup and Saucer, of which the following is a specification, reference being had to the accompanying drawing forming part thereof.

Fig. 1 is a perspective view of a combined egg serving cup and saucer, showing my new design.

Fig. 2 is a perspective view illustrating the device shown in Fig. 1 in an open position.

I claim:

The ornamental design for a combined egg serving cup and saucer, substantially as shown.

THORWALD R. NELSON.
